Inventor:
R. M. Snodgrass

United States Patent Office.

ROBERT M. SNODGRASS, OF PITTSBURG, PENNSYLVANIA.

Design No. 3,910, dated March 15, 1870.

DESIGN FOR A BAGGAGE-RACK.

The Schedule referred to in these Letters Patent and making part of the same.

To all whom it may concern:

Be it known that I, ROBERT M. SNODGRASS, of Pittsburgh, in the county of Allegheny, and State of Pennsylvania, have invented a new and useful Design for Baggage-Rack; and I do hereby declare the following to be a full, clear, and exact description thereof.

My improved design for racks for railroad cars consists of a basket for receiving and holding packages, parcels, articles of clothing, &c., connecting with a frame-work in front for the insertion of advertising cards, and a looking-glass frame below.

To enable others skilled in the art to make and use my invention, I will proceed to describe the same, the drawings hereunto annexed and forming part of this specification being a photograph thereof.

The ends *a* of the rack are made of any desired style of ornamental cast-metal work, as also the back *b*, by any suitable part of which the rack is suspended or fastened to the side of the car.

In this frame-work is attached a wire basket, *c*, the proper concave form for receiving packages, parcels, articles of clothing, &c.

In front of the basket, by end bars *e* and top and bottom bars *e'*, I make a card or advertising-frame, in which to insert and fasten, by any suitable means, a

business-card or advertisement, *m*, or by dividing the space, two or more such cards may be inserted at pleasure; and in either case they may be permanently attached or be removable, as may be preferred.

The lower part of the back *b* has a frame, *i*, for the insertion of a looking-glass, *n*.

The design thus described and shown is neat in appearance, and useful not only for the ordinary purposes of a rack, but also as an advertising medium, the conspicuous position given to the advertisement adding greatly to its value.

This design I apply not only in railroad cars, but also in other vehicles or means of passenger transportation where such racks are desirable.

What I claim as my invention, and desire to secure by Letters Patent, is—

A baggage-rack, having on the front of its basket a card or advertising-frame, and a looking-glass frame below, substantially as shown and described.

In testimony whereof I, the said ROBERT M. SNODGRASS, have hereunto set my hand.

R. M. SNODGRASS.
